UNITED STATES PATENT OFFICE

138,811

DESIGN FOR A TOY

Albert A. Share, Chicago, Ill.

Application June 26, 1944, Serial No. 114,199

Term of patent 7 years

(Cl. D34—15)

To all whom it may concern:

Be it known that I, Albert A. Share, a citizen of the United States of America, residing at 5100 Cornell Avenue, Chicago, Illinois, have invented a new, original, and ornamental Design for a Toy, of which the following is a specification, reference being had to the accompanying drawing forming a part thereof.

Referring to the drawing, Fig. 1 is a side elevational view of a toy embodying my new design; Fig. 2 is an elevational view of the reverse side of the same; Fig. 3 is a front elevational view and Fig. 4 is a rear elevational view.

I claim:

The ornamental design for a toy, substantially as shown.

ALBERT A. SHARE.
